UNITED STATES PATENT OFFICE.

COURTLAND J. CRAWLEY, OF CHICAGO, ILLINOIS.

RECEPTACLE.

Application filed November 28, 1921. Serial No. 518,443.

To all whom it may concern:

Be it known that I, COURTLAND J. CRAWLEY, a citizen of the United States, residing at Chicago, in the county of Cook and State of Illinois, have invented certain new and useful Improvements in Receptacles, of which the following is a description.

My invention relates to improvements in receptacles and more particularly to improvements for detaching or removing the cover or closure caps of said receptacles.

One of the objects of my invention is to provide a resilient or flexible member which when flexed will separate said cover and receptacle so that the cover may be easily removed.

Among other objects of my invention is the production of a device of the kind described which is simple, economical, durable, efficient and reliable for use wherever found applicable.

Many other objects of the construction herein shown and described will be obvious to those skilled in the art to which this invention belongs from the disclosure herein given.

To this end my invention consists in the novel construction, arrangement and combination of parts herein shown and described and more particularly pointed out in the claims.

In the drawings, wherein like reference characters indicate like or corresponding parts;

Figure 1 is a top plan view of my device as arranged with a cover and a receptacle;

Figure 2 is a sectional view taken substantially on the line 2—2 of Figure 1;

Figure 3 is a front elevation; and

Figure 4 is a sectional view taken substantially on the line 4—4 of Figure 3.

In the drawings wherein I have illustrated the preferred embodiment of my invention, there is shown a container 1 having an open end or top 2 with a peripheral bead 3 thereon, arranged at a suitable distance from said open end. Adapted to frictionally engage the open end of the container or receptacle 1 is a cover or cap 4 having an annular flange 5 frictionally engageable with the exterior surface of the open end 2 of the container and limited in its downward movement by the bead 3. An annular bead 6 is formed at the bottom of the container 1 for a purpose which will be hereinafter described, said bead being slightly upturned

toward its free edge, in radial cross-section.

Ordinarily the cap or cover which frictionally engages the open end of a container is extremely difficult to remove, especially if it is smooth or if it is wet or greasy. In order to overcome this difficulty I have arranged a short bar or strip 7 of flexible resilient spring metal which is preferably bent in the form of a bow, as shown more clearly in Figure 2. One end of the spring 7 is secured to the cap or cover 4 by any suitable means, as by welding, brazing, riveting, or the like, and the free end of said spring abuts the annular bead 6 so that when the spring 7 is pressed inwardly or flexed to the dotted line position shown in Figure 2 it will yieldably straighten out and separate the cover and container. It is obvious that should the receptacle or container be of greater length than shown, that any other form of fixed abutment may be provided in place of the bead 6 shown at the bottom of the container. This fixed abutment may be in the form of a bead projecting either inwardly of the container or outwardly thereof, or it may be any other suitable form of fixed abutment.

Having thus described my invention it is obvious that various immaterial modifications may be made in the same without departing from the spirit of my invention; hence I do not wish to be understood as limiting myself to the exact form, construction, arrangement and combination of parts herein shown and described or uses mentioned.

What I claim as new and desire to secure by Letters Patent is:

1. In a device of the kind described and in combination, a container, a cover therefor, said container having a circumferentially-extending bead spaced downwardly of the open end against which bead said free end of the cover is adapted to abut when the box is closed, and a flexible spring strip secured to the top of one of said members and projecting downwardly of the side thereof, said container having a peripheral bead thereon adapted to abut the free end of said spring, said spring having an outwardly-extending projection therein adapted to overlie said first-mentioned bead when said spring is pressed inwardly into contact with said cover and container to separate said members.

2. In a device of the kind described and in combination, a container, a cover therefor, the container having a circumferentially ex-

tending bead spaced downwardly of its open end, and a flexible spring strip secured to one of said members and projecting longitudinally of the side thereof, the other of
5 said members having a peripheral bead thereon to abut the free end of said spring, said spring having an outwardly-extending projection therein adapted to overlie said first-mentioned bead when said spring is

pressed inwardly into contact with said 10 cover and container to separate said parts.

In testimony whereof, I have hereunto signed my name in the presence of two subscribing witnesses.

COURTLAND J. CRAWLEY.

Witnesses:
